G. L. FARRAR

FIRE EXTINGUISHING ATTACHMENT FOR MOTION PICTURE MACHINES

Filed March 2, 1925

UNITED STATES PATENT OFFICE.

GEORGE L. FARRAR, OF COLUMBUS, OHIO.

FIRE-EXTINGUISHING ATTACHMENT FOR MOTION-PICTURE MACHINES.

Application filed March 2, 1925. Serial No. 12,523.

To all whom it may concern:

Be it known that I, GEORGE L. FARRAR, a citizen of the United States, residing at Columbus, in the county of Franklin and State of Ohio, have invented certain new and useful Improvements in Fire-Extinguishing Attachments for Motion-Picture Machines, of which the following is a specification.

This invention relates to motion picture machines and has for its principal object the provision of a simple, positively operating mechanism positioned contiguous to the reel magazines of such machines and cooperative with the film between the upper and lower magazines of the machine, whereby in the event of the film catching on fire, as it frequently does when exposed unduly to the lens and light temperatures, to confine the fire to a comparatively small portion of the film, which can be readily repaired, and prevent the fire from reaching the main body of the film contained within either of said magazines.

More specifically, my invention consists in placing the film between relatively separable fire extinguishing rollers, which rollers are mounted in movable supports disposed within the housing of the machine adjacent to the magazine entrance slots, the arrangement being such that if the film catches on fire only that portion thereof within the housing of the machine will be damaged, as the extinguishing rollers will prevent the fire from reaching the film within the magazines.

Another object of the invention rests in the provision of means for maintaining the extinguishing rollers in separated positions when the film is being threaded through the guides of the machine, and in mounting the rollers in connection with resiliently pressed guides or boxes which serve normally to maintain the rollers in close frictional engagement with both sides of the film.

With these and other objects in view, as will appear as the description proceeds, the invention consists in the novel features of construction, combinations of elements and arrangements of parts hereinafter to be fully described and pointed out in the appended claims.

In the accompanying drawing:

Figure 1 is a view showing diagrammatically a motion picture projection machine and illustrating the application thereto of 55 the film engaging and fire arresting mechanism comprising the present invention.

Figure 2 is a plan view of one of the units comprising said mechanism,

Figure 3 is a side elevation thereof, 60

Figure 4 is a vertical longitudinal sectional view on the line 4—4 of Figure 2,

Figure 5 is a transverse section on the line 5—5 of Figure 2, and

Figure 6 is a similar view on the line 6—6 65 of Figure 2.

Referring more particularly to the drawings the numeral 1 designates generally a motion picture projecting machine which has been illustrated to a sufficient extent to 70 indicate the arrangement and use of the attachments comprising the present invention. As shown, the machine includes a supporting pedestal 2, upon which is mounted a housing or casing 3, and located within the 75 housing is a longitudinally extending lens tube 4, situated in registration with an aperture plate 5 and the condensing lens structure 6 of the lamp housing 7. The outer end of the tube 4 cooperates with the usual 80 rotating shutter 8, and the housing is equipped with upper and lower reel magazines 9 and 10 respectively. These magazines are provided with reel entries or slots 11, through which the motion picture film passes 85 from the housing 3 into the magazines, and arranged within the housing 3 are guide sprockets 12, around which the film is trained, as usual, so as to pass between the aperture plate 5 and the film guiding plate 90 13 located at the inner end of the tube 4. This construction is common in motion picture machines generally and therefore a more extended description relative thereto has been omitted.

95 Due to the intense heat of the light projected from the lens structure 6 and the concentration of the light rays on the film, it frequently happens that if the progress of the film through the housing is interfered with in any manner the heat concentrated thereon will result in causing the film to take 100

fire, and because of the combustible nature of the materials from which the film is formed, the fire is rapidly transmitted, in fact, almost instantaneously, to the body of film contained in the magazines 9 and 10. This may result in a fire of considerable proportions and result in injury to the operator of the machine and frequently to the patrons of the theater in which the machine is located.

The present invention provides an automatically operating structure for preventing the fire resulting from the burning of the film in the housing from reaching the film in the magazines. To accomplish this in a simple and practical manner I provide the housing adjacent each of the film slots 11 with automatically operating fire extinguishing attachments by means of which the progress of a film fire within the housing is arrested and the likelihood of a large fire eliminated. The attachments are of identical construction and therefore a description of one will suffice for the other. Each attachment consists of a base plate 14, secured in any suitable manner within the housing and provided with a slot 15 adapted to register with one of the slots 11. One end of the base plate 14 is provided with vertical walls 16, which are recessed as at 17 to receive sliding blocks 18, in which are mounted the shafts 19 of a pair of vertically aligned rollers 20. These rollers are preferably formed from a soft pliable composition such as soft yieldable rubber, and the blocks 18 are pressed forwardly by means of springs 21, the forward movement of said blocks being limited by means of rigid strips 22 secured to the walls 16. By this construction it will be noted that the rollers 20 are mounted in vertical alignment for rotation about horizontal axes and that the rollers are permitted to move horizontally a limited distance governed by the contraction of the springs 21 and the limiting action of the strips 22.

Slidably mounted upon the plate 14 by the provision of dove tailed ribs 23 is a block 24, which has its side walls recessed as at 25 for the longitudinal sliding reception of shaft journals 26, in which are mounted for rotation the ends of shafts 27 which carry rollers 28 corresponding in construction to the rollers 20 and arranged for registration with said rollers 20. Springs 29 are mounted in the recess 25 and normally force the journals forwardly, this forward movement being limited by fixed strips 31 carried in connection with the side walls of the block 24. By this construction the normal influence of the springs 21 and 29 is to maintain the rollers 20 and 28 in close relative engagement.

Projecting from the block 24 are guide pins 31', which extend loosely through open-

ings 32 formed in the rear wall 33 of the plate 14. Surrounding the pins 31' and situated between the wall 33 and the block 24 are expansion springs 34 which are materially stronger than the journal springs 21 and 29 and it is the office of the springs 34 to force the rollers 20 and 28 together and to apply frictional pressure to the film passing therebetween.

It will be seen that in the event of the film within the housing catching fire, the progress of this fire will be arrested by the smothering or pinching action of the rollers 20 and 28. While each attachment may be provided with but a single pair of cooperative rollers and may perform efficiently, nevertheless, a second pair has been provided so as to render the action of the attachment doubly effective and positive. It will be seen that by reason of the soft pliable material from which the rollers are formed or coated quite a wide surface will be presented to both sides of the film which insures extinguishment of the fire. In normal operation the rollers are in constant engagement with the film as shown in Figure 3 so that positive operation is assured. The light springs 21 and 29 are employed to compensate for slight irregularities in the thickness of the film. Frequently film is patched to mend breaks, and this results in double thickness, and therefore, by the provision of the lighter springs the rollers are permitted to separate slightly without regard to the main springs 34 to allow the film to pass through the rollers without undue friction. When it is desired to thread the film through the machine I provide means for maintaining the rollers relatively separated so that they will not interfere with the operator in drawing the film through the guides contained within the housing 3. This is accomplished by moving the block 24 rearwardly along its guide ribs 23 and compressing the springs 34, the side walls of the block being provided with recesses or depressions 35 by means of which the block may be conveniently gripped between the fingers of the operator. Then, on top of the block 24 is a resilient catch 36, shown more particularly in Figure 4. This catch is provided with a vertical edge capable of cooperating with a similar face 37 provided on said block to hold the latter in its retracted position. The latch or catch 36 thus serves to retain the rollers separated and leaves the operator free to work with both hands in the threading of the film. After the film has been threaded through the machine, the catch or latch is lifted and the block responds to the pressure of the springs 34 and returns for cooperation with the rollers 20.

It will thus be seen that the present invention provides simple and positive means capable of operating reliably to extinguish

film fire in the housing of a motion picture machine. The device operates without manual attention and is of such construction as to avoid interference with the normal passage of the film through the machine.

What is claimed is:

1. A fire extinguishing attachment for motion picture machines comprising a frame, a block slidably mounted on said frame, a stationary roller mounted on said frame, a second roller cooperative with said first named roller and carried by said block, spring means acting on said block to maintain said rollers in mutual contact, and supplemental spring means cooperative with said rollers for permitting of slight relative separation independently of said first named spring means.
2. A fire extinguishing attachment for motion picture machines comprising a relatively fixed roller and a movable roller between which the film passes, major spring means for maintaining said rollers in mutual contact with said film, and minor spring means cooperative with said rollers for permitting of slight relative separation on the part of said rollers independently of said major spring means.

3. A fire extinguishing attachment for motion picture machines consisting of a frame, a pair of relatively stationary rollers mounted on said frame, a block slidably mounted on said frame, a pair of rollers carried by said block and arranged for co-operation with said first named rollers, major spring means between said frame and said block serving normally to maintain said rollers in mutual contact with a film passing between them, and minor spring means cooperative with said rollers to permit of slight relative movement therebetween independently of said major spring means.

4. A fire extinguishing attachment for motion picture machines consisting of a frame, a relatively stationary roller mounted on said frame, a support slidably mounted on said frame, a roller carried by said support and cooperative with said first named roller, separation means between said frame and support and serving to maintain said rollers in mutual engagement, and a locking device carried by said frame and cooperative with said support for maintaining said rollers out of engagement.

In testimony whereof I affix my signature.
GEORGE L. FARRAR.
